WINDOW CONSTRUCTION

Clyde W. Kelly, Detroit, Mich., assignor to Detroit Steel Products Company, Detroit, Mich., a corporation of Michigan

Application January 8, 1932, Serial No. 585,605

12 Claims. (Cl. 189—69)

The invention relates to window constructions and refers more particularly to window constructions having outwardly opening sashes and provided with screens inside the sashes. One of

5 the objects of the invention is to provide an improved practical window construction of this type in which the screen is movable outwardly after the sash is opened, so that the shades, draperies, and so forth, at the inside of the window construction need not be disturbed and the sash may be readily accessible from the inside for cleaning and so forth. Other objects are to so mount the screen that one of its edges may be secured to the frame of the window construction

10 and may be moved laterally thereof; to effectively weather strip the joint between the frame and sash; to construct the screen with weather stripping means for the joint; and to construct the guiding means for the screen with weather stripping means for the joint.

These and other objects of the invention will become apparent from the following description, taken in connection with the accompanying drawings, in which

25 Figure 1 is an inside elevation of a window construction showing an embodiment of my invention;

Figures 2 and 3 are cross sections on the lines 2—2 and 3—3, respectively, of Figure 1;

30 Figure 4 is a view similar to Figure 3, showing the sash and screen in open positions;

Figure 5 is a view similar to Figure 3, showing another embodiment of my invention;

Figure 6 is a view similar to Figure 5, showing another embodiment of my invention;

Figure 7 is a view similar to Figure 2, showing another embodiment of my invention.

The invention is particularly applicable to casement windows which comprise the metallic

40 skeleton frame 1 adapted to be suitably anchored in the sill and the metallic skeleton sash or sashes 2 mounted on the frame. As shown in Figures 1 and 3, the casement window is of the double ventilator type in which each sash is pivotally

45 mounted upon the frame by the hinges 3 to swing horizontally outwardly to open position. The frame comprises the bars 4, each of which has the main or outer flanged portion 5 and the inner flanged or L-shaped portion 6 integral therewith

50 and at the inside thereof. The main or outer flanged portion specifically has the oppositely directed lateral flanges 7 and 7', respectively, at the inner and outer edges of its web 8, so that the main or outer portion is Z-shaped. The sash

55 comprises the flanged bars 9, each of which

specifically also has the oppositely directed lateral flanges 10 and 10' at the inner and outer edges of its web 11, so that each bar 9 is Z-shaped. The flanges 7 and 7' of the main portion 5 of the bars 4 and the flanges 10 and 10' of the bars 9 form cooperating inner and outer weathering portions, which in the closed position of the sash are adapted to overlap and form joints.

Each sash is adapted to be opened and closed from inside the casement window by suitable means such as the operator 12, which is mounted on and movable relative to the bottom or sill bar

4 of the frame and is operatively connected to the bottom bar 9 of the sash. Each sash may also be locked in closed position by suitable

10 means, such as the fastener 13 having a shank extending through the inside flange of the dividing or middle bar 14 of the frame and provided with the cam 15 for engaging a shoulder upon the adjacent side bar of the sash. This shoulder

15 may be formed either by the baffle 16 of this side bar or by the keeper member 17 secured to this side bar. The fastener shank clears the L-shaped portion 6 of the dividing or middle bar.

20 As shown in Figures 1, 2, 3 and 4, 18 is the screen which is mounted upon the frame 1 inside the sash 2 when in closed position. This screen has in the present instance the metallic frame

19 and the screen mesh 20 and it is mounted on and overlaps the L-shaped portions 6 of the bars forming the frame 1. The screen is pivotally connected to the frame at its edge adjacent to the hinges 3 pivotally connecting the sash to the frame, so that the screen may be opened by

25 swinging the same outwardly. In detail, 21 are vertically headed pins in axial alignment extending upwardly and downwardly from the upper and lower bars 19 of the screen frame near their ends adjacent the hinges 3. The heads of these pins slidably engage the metallic guides 22 which

30 are secured to the horizontally extending portions of the L-shaped portions 6. These guides extend longitudinally of these horizontally extending portions a sufficient distance such that they provide for sufficient movement of the pivoted edge of the screen laterally of the frame,

35 so that the screen may, as shown particularly in Figure 4, occupy an open position substantially parallel to and spaced from the sash and at substantially right angles to the frame 1. The

40 sliding movement of the pivoted edge of the screen frame is preferably limited by suitable means, such as the stop screw 23 at the free end of each of the guides 22. The swinging edge of the screen

45 may be suitably held in place when the screen is

closed as by means of the fasteners 24, which are adapted to overlap the vertically extending portion of the L-shaped portion 6 of the frame bar engageable by the free or swinging edge of 5 the sash.

In the modification shown in Figure 5, the 10 construction of the casement window is the same as previously described, but the screen 25, instead of being pivotally and slidably connected to the casement window frame, is detachably connected thereto by the fasteners 26 at both side edges of the screen, the construction being such that by disengaging these fasteners from the window frame the screen may be removed upon opening 15 of the sash by moving the screen outwardly.

Figure 6 discloses a modification of Figure 5 in which the frame 27 of the screen 28 is provided with the yieldable weather strips 29, which are located between the inner weathering portions of 20 the frame 30 and the sash 31. These weather strips are preferably flexible and formed of spring bronze and may be, if desired, integral with the material forming the frame 27 of the screen.

Figure 7 discloses another modification of Figures 1, 2, 3 and 4, in which the weather stripping 25 means between the inner cooperating weathering portions of the frame 32 and the sash 33 comprises the flexible weather strips 34, which may be formed of spring bronze and which are secured 30 to the guides 35 or one edge of the screen 36.

With the above constructions, the screens may 35 be removed, if desired, and replaced by similarly formed storm windows during the winter, in which event the storm windows may be opened with the sashes to provide for ventilation.

What I claim as my invention is:

1. In a window construction, the combination 40 with a frame and an outwardly opening sash mounted on said frame, said frame and sash having a plurality of cooperating weathering portions, of an outwardly opening screen mounted on and overlapping said frame at the inside of said sash, and cooperating means on said frame and screen for guiding one edge of said screen and 45 providing for movement thereof laterally relative to said frame.

2. In a window construction, the combination 50 with a frame and an outwardly opening sash mounted on said frame, said frame and sash having cooperating weathering portions, of an outwardly opening screen mounted on said frame at the inside of said sash, and cooperating means on said frame and screen for guiding one edge of said screen and providing for movement thereof 55 laterally of said frame, flexible weather stripping means forming a part of said guiding means and extending between said cooperating weathering portions.

3. In a window construction, the combination 60 with a frame, comprising bars having flanged main portions and flanged portions inside said main portions, of an outwardly opening sash mounted on said frame and comprising flanged bars, said last mentioned bars and said main portions having cooperating weathering portions, and an outwardly movable screen mounted on and overlapping said flanged portions at the inside of said sash.

4. In a window construction, the combination 70 with a frame, comprising bars having Z-shaped portions and L-shaped portions inside said Z-shaped portions, of an outwardly opening sash mounted on said frame and comprising Z-shaped bars, said last mentioned bars and said Z-shaped 75 portions having cooperating weathering portions,

and an outwardly movable screen mounted on and overlapping said L-shaped portions at the inside of said sash.

5. In a window construction, the combination 5 with a frame, comprising bars having flanged main portions and flanged portions inside said main portions, of an outwardly opening sash mounted on said frame and comprising flanged bars, said last mentioned bars and said main portions having cooperating inner and outer weathering portions, an outwardly movable screen mounted on and overlapping said flanged portions at the inside of said sash, and yieldable weather stripping means between said inner cooperating weathering portions. 15

6. In a window construction, the combination 20 with a frame, comprising bars having Z-shaped portions and L-shaped portions inside said Z-shaped portions, of an outwardly opening sash mounted on said frame and comprising Z-shaped bars, said last mentioned bars and said Z-shaped portions having cooperating inner and outer weathering portions, an outwardly movable screen mounted on and overlapping said L-shaped portions 25 at the inside of said sash, and yieldable weather stripping means between said inner cooperating weathering portions.

7. In a window construction, the combination 30 with a frame, comprising bars having flanged main portions and flanged portions inside said main portions, of an outwardly opening sash mounted on said frame and comprising flanged bars, said last mentioned bars and said main portions having cooperating inner and outer weathering portions, and an outwardly movable 35 screen having a frame mounted on and overlapping said flanged portions at the inside of said sash, said last mentioned frame having a flexible weather strip between said inner cooperating weathering portions. 40

8. In a window construction, the combination 45 with a frame, comprising bars having Z-shaped portions and L-shaped portions inside said Z-shaped portions, of an outwardly opening sash mounted on said frame and comprising Z-shaped bars, said last mentioned bars and said Z-shaped portions having cooperating inner and outer weathering portions, and an outwardly movable screen having a frame mounted on and overlapping 50 said L-shaped portions at the inside of said sash, said last mentioned frame having a flexible weather strip between said inner cooperating weathering portions. 55

9. In a window construction, the combination 60 with a frame, comprising bars having flanged main portions and flanged portions inside said main portions, of an outwardly swinging sash mounted on said frame and comprising flanged bars, an outwardly swinging screen mounted on and overlapping said flanged portions at the inside of said sash, and cooperating means on said second mentioned flanged portions and screen for guiding one edge of said screen and providing for movement thereof laterally of said frame. 65

10. In a window construction, the combination 70 with a frame, comprising bars having Z-shaped portions and L-shaped portions inside said Z-shaped portions, of an outwardly swinging sash mounted on said frame and comprising Z-shaped bars, an outwardly swinging screen mounted on and overlapping said L-shaped portions at the inside of said sash, and cooperating means on 75 said L-shaped portions and screen for guiding one edge of said screen and providing for movement thereof laterally of said frame. 80

11. In a window construction, the combination with a frame, comprising bars having flanged portions and flanged portions inside said main portions, of an outwardly opening sash, comprising flanged bars mounted on said frame, said sash bars and main portions having cooperating weathering portions, an outwardly opening screen mounted on and overlapping said second mentioned flanged portions and located at the inside of said sash, and cooperating means on said second mentioned flanged portions and screen for guiding one edge of said screen and providing for movement thereof laterally of said frame, flexible weather stripping means forming a part of said guiding means on said second mentioned flanged portions for weatherproofing the space between said cooperating weathering portions.
12. In a window construction, the combination with a frame, comprising bars having Z-shaped portions and flanged portions inside said Z-shaped portions, of an outwardly opening sash, comprising flanged bars mounted on said frame, said sash bars and Z-shaped portions having cooperating weathering portions, an outwardly opening screen mounted on and overlapping said second mentioned flanged portions and located at the inside of said sash, and cooperating means on said second mentioned flanged portions and screen for guiding one edge of said screen and providing for movement thereof laterally of said frame, flexible weather stripping means forming a part of said guiding means on said second mentioned flanged portions for weatherproofing the space between said cooperating weathering portions.

CLYDE W. KELLY.
